FOLIC ACID INTERMEDIATES

David I. Weisblat, Barney J. Magerlein, and Arthur R. Hanze, Kalamazoo, Mich., assignors to The Upjohn Company, Kalamazoo, Mich., a corporation of Michigan

No Drawing. Application December 3, 1948,
Serial No. 63,454

40 Claims. (Cl. 260—251.5)

1

This invention relates to a method for the preparation of N-((2-amino-4-hydroxy-6-pteridyl)methyl - N - (arylsulfonyl) - p - aminobenzoate compounds and to certain intermediates useful in the method.

The N-((2-amino-4-hydroxy-6-pteridyl)methyl) - N - (arylsulfonyl) - p - aminobenzoate compounds which can be prepared by the method of the invention have the generic formula

wherein R' is from the group consisting of hydrogen and the alkyl radicals and n is from the group consisting of zero and the positive integers 1 to 7, inclusive, and thus include N-substitution products of p-aminobenzoic acid, of p-aminobenzoyl glutamic acid, of the p-aminobenzoyl-glutamyl-glutamic acids having up to seven glutamic acid residues in the molecule, and of their esters. In the naming of compounds having the generic formula given, which are described and claimed in copending application Serial No. 41,882, filed July 31, 1948, now Patent No. 2,558,711, and of other starting compounds and intermediate compounds mentioned herein wherein both a glutamic acid residue and a p-aminobenzoic acid residue are included in the molecule, the nitrogen atom of the glutamic acid residue is, for convenience, herein referred to by the symbol "N'" and the nitrogen atom of the p-aminobenzoic acid residue is referred to by the symbol "N." As indicated by the generic formula, compounds used in or prepared by the process of the invention which contain more than one glutamic acid or ester residue contemplated by the invention are those wherein only the gamma-carboxyl groups are involved in the peptide linkages. Preferred

2

compounds used in or prepared by the method of the invention are those wherein n of the generic formula given, and in those given subsequently, represents zero or the integer 1, i. e. those containing either no glutamic acid or ester residue or only one glutamic acid or ester residue, and the method and intermediate compounds will be described with particular reference thereto.

Compounds having the generic formula given above and compounds useful as intermediates in the preparation thereof, are of particular value due to the relationship of the former with, and to the ease with which they can be converted to, compounds similar to or identical with certain naturally occurring compounds of the folic acid group. Thus, diethyl N'-((2-amino-4-hydroxy-6-pteridyl)methyl) - N - (p-toluenesulfonyl) - p - aminobenzoyl - 1 - glutamate can be converted readily by hydrolysis of the two ethyl ester groups with alkali to the corresponding dicarboxy compound and the latter, by splitting the p-toluenesulfonyl radical from the molecule with hydrogen bromide and a bromine acceptor in an aliphatic acid medium, according to the method described and claimed in copending application, Serial No. 41,883, filed July 31, 1948, now Patent No. 2,562,222, can be converted readily to a pteroyl-glutamic acid which appears to be identical with the "L. casei factor" or vitamin B_c from liver. The order of the hydrolysis step and splitting of the arylsulfonyl radical can be reversed, if desired.

Compounds having the generic formulae given in which the glutamic acid residues have the (1+) configuration are of particular interest because of the existence of glutamic acid residues having the same configuration in folic acid compounds isolated from natural sources. The method of the invention and the intermediate compounds to be described are, however, not limited as to the configuration of the glutamic acid residues involved.

N-(3,3-dialkoxy-2-hydroxypropyl)-N-(arylsulfonyl)-p-aminobenzoate compound

N-(2-formyl-2-hydroxyethyl)-N-(arylsulfonyl)-p-aminobenzoate compound

The process of the invention, as illustrated in the accompanying reaction chart wherein the formulae of the compounds given are numbered to correspond with the following description and wherein R' and n have the values previously given, comprises, among others, the step of reacting or condensing an N-(2-formyl-2-ketoethyl)-N-(arylsulfonyl)-p-amino-benzoate compound (III) with 2,4,5-triamino-6-hydroxypyrimidine (VII) to form an N-((2-amino-4-hydroxy-6-pteridyl)methyl)-N-(arylsulfonyl)-p-aminobenzoate compound (VIII).

The N-(2-formyl-2-ketoethyl) - N - (arylsulfonyl)-p-aminobenzoate compound (III) can be prepared in any one of several ways contemplated by the invention. One such way comprises hydrolyzing the acetal group of an N-(3,3-dialkoxy-2-ketopropyl)-N-(arylsulfonyl)-p-aminobenzoate compound (IV) with an aqueous mineral acid. An N-(2-formyl-2-ketoethyl)-N-(arylsulfonyl)-p-aminobenzoate compound (III) can also be prepared by oxidizing an N-(3-hydroxy-2-ketopropyl)-N-(arylsulfonyl)-p-aminobenzoate compound (V), e. g. with chromic or cupric acetate, in an aqueous alkanol. A further method for preparing an N-(2-formyl-2-ketoethyl)-N-(arylsulfonyl)-p-aminobenzoate compound (III) consists in oxidizing an N-(3-methoxy-2-ketopropyl)-N-(arylsulfonyl)-p-aminobenzoate compound (VI), e. g. with chromic acetate in an aqueous medium. Still a further method for preparing an N-(2-formyl-2-ketoethyl)-N-(arylsulfonyl)-p-aminobenzoate compound (III) consists in oxidizing an N-(2-formyl-2-hydroxyethyl)-N-(arylsulfonyl)-p-aminobenzoate compound (II), e. g. with chromic or cupric acetate in an alcoholic or aqueous alcoholic medium.

An N-(3,3-dialkoxy-2-ketopropyl)-N-(arylsulfonyl)-p-aminobenzoate compound (IV) can be prepared, as described and claimed in a concurrently filed copending application, Serial No. 63,453, by heating a 2,3-oxidopropanal dialkyl

acetal (IX) having the formula

$$\begin{array}{c}
 \text{O} \\
 \diagup \quad \diagdown \\
 \text{CH}_2 - \text{CH} \text{CH}_2 (-\text{O-alkyl})_2
 \end{array}
 \quad \text{IX}$$

35 2,3-oxidopropanal dialkyl acetal
with an N-(arylsulfonyl)-p-aminobenzoate alkyl ester (X) having the formula

$$\begin{array}{c}
 \text{C O O-alkyl} \\

 \text{H} - \text{N} \text{---} \text{C}_6\text{H}_4 \text{---} \text{C O} (\text{NH} \text{---} \text{C H} \text{---} \text{C H}_2 \text{---} \text{C O})_n \text{---} \text{O-alkyl} \\
 | \\
 \text{aryl---S O}_2
 \end{array}
 \quad \text{X}$$

40 N-(arylsulfonyl)-p-aminobenzoate alkyl ester
followed by hydrolysis of the product with dilute
45 alkali if the free acid is desired, to form an
N-(3,3-dialkoxy-2-hydroxypropyl)-N-(arylsul-
fonyl)-p-aminobenzoate compound (I) and sub-
sequently oxidizing the latter hydroxy acetal, e.g.
with chromic oxide, to form the keto acetal (IV).
50 An N-(2-formyl-2-hydroxyethyl)-N-(arylsul-
fonyl)-p-aminobenzoate compound (II) can, as
is herein first disclosed, be prepared by treating
an N-(3,3-dialkoxy-2-hydroxypropyl)-N-(arylsul-
fonyl)-p-aminobenzoate compound (I) with
55 an aqueous mineral acid, preferably at an ele-
vated temperature.

An N-(3-hydroxy-2-ketopropyl)-N-arylsulfonyl-p-aminobenzoate compound (V) can be prepared by first reacting an N-(arylsulfonyl)-p-aminobenzoate compound (XI) having the formula

COOR'

$$\text{H}-\text{N} \begin{array}{c} \diagup \\ \text{C} \end{array} \text{O}(\text{NHCHCH}_2\text{CH}_2\text{CO})_n\text{OR}'$$

65 **XI**

N-(arylsulfonyl)-p-aminobenzoate compound

with an epihalohydrin (XII)

$$70 \quad \text{CH}_2\text{CHCH}_2\text{---hal}$$

XII

according to the method described and claimed in copending application Serial No. 41,884, filed July 31, 1948, to form an N-(3-halo-2-hydroxy-

propyl) - N-(arylsulfonyl) - p-aminobenzoate compound (XIII) having the formula

XIII

N-(3-halo-2-hydroxypropyl)-N-(arylsulfonyl)-p-aminobenzoate compound

The latter compound can then, as described and claimed in copending application Serial No. 41,889, filed July 31, 1948, be oxidized with chromic oxide in glacial acetic acid to form an N-(3-halo-2-ketopropyl) - N-(arylsulfonyl) - p-aminobenzoate compound (XIV) having the formula

XIV

N-(3-halo-2-ketopropyl)-N-(arylsulfonyl)-p-aminobenzoate compound

which, upon hydrolysis with aqueous alkali under carefully controlled conditions, is converted smoothly to an N-(3-hydroxy-2-ketopropyl) - N-(arylsulfonyl) - p-aminobenzoate compound (V).

Alternatively, an N-(3-hydroxy-2-ketopropyl) - N-(arylsulfonyl) - p-aminobenzoate compound (V) can be prepared by first reacting an N-(arylsulfonyl) - p-aminobenzoate compound (XI) with an epoxypropyl aliphatic ester (XV) having the formula

XV

Epoxypropyl aliphatic ester

according to the method described and claimed in copending application Serial No. 41,890, filed July 31, 1948, to form an N-(3-acyloxy-2-hydroxypropyl)-N-(arylsulfonyl)-p-aminobenzoate compound (XVI) having the formula

XVI

N-(3-acyloxy-2-hydroxypropyl)-N-(arylsulfonyl)-p-aminobenzoate compound

The latter compound can then, as described and claimed in copending application Serial No. 41,889, previously referred to, be oxidized with chromic oxide to form an N-(3-acyloxy-2-ketopropyl) - N-(arylsulfonyl) - p-aminobenzoate compound (XVII) having the formula

XVII

N-(3-acyloxy-2-ketopropyl)-N-(arylsulfonyl)-p-aminobenzoate compound

which, upon ester interchange with an alkanol, is converted to an N-(3-hydroxy-2-ketopropyl) - N-(arylsulfonyl) - p-aminobenzoate compound (V).

An N-(3-methoxy-2-ketopropyl) - N - (arylsulfonyl) - p-aminobenzoate compound (VI) can be prepared conveniently by treating an N-(3-halo-2-hydroxypropyl) - N - (arylsulfonyl) - p-aminobenzoate compound (XIII) with an

aqueous alkali under carefully controlled conditions, as described and claimed in copending application Serial No. 41,884, previously referred to, to form an N-(2,3-epoxypropyl) - N - (arylsulfonyl) - p-aminobenzoate compound (XVIII) having the formula

XVIII

N-(2,3-epoxypropyl)-N-(arylsulfonyl)-p-aminobenzoate compound

which can be reacted readily with sodium methylate, according to the method described and claimed in the same application Serial No. 41,884, to form an N-(3-methoxy-2-hydroxypropyl) - N-(arylsulfonyl) - p - aminobenzoate compound (XIX) having the formula

XIX

N-(3-methoxy-2-hydroxypropyl)-N-(arylsulfonyl)-p-aminobenzoate compound

The latter methoxy alcohol can be oxidized with chromic oxide by the method described and claimed in copending application Serial No. 41,889, previously referred to, to form an N-(3-methoxy-2-ketopropyl) - N-(arylsulfonyl) - p-aminobenzoate compound (VI).

The N-(arylsulfonyl) - p-aminobenzoate compounds (XI), including the N-(arylsulfonyl)-p-aminobenzoate alkyl esters (X) are prepared conveniently by a method described and claimed in copending application Serial No. 41,888, filed July 31, 1948, which consists in reacting an arylsulfonyl halide with a p-aminobenzoate compound (XX) having the formula

XX

p-Aminobenzoate compound

Of the starting materials used in the process of the present invention and intermediate compounds mentioned as useful in the preparation thereof, certain of the N-(arylsulfonyl) - p-aminobenzoate compounds (XI) including certain of the N-(arylsulfonyl) - p - aminobenzoate alkyl esters (X), are described and claimed in copending application Serial No. 41,888, filed July 31, 1948; the N-(3-acyloxy-2-hydroxypropyl) - N-(arylsulfonyl) - p - aminobenzoate compounds (XVI), the N-(3-halo-2-hydroxypropyl) - N-(arylsulfonyl) - p - aminobenzoate compounds (XIII), the N-(2,3-epoxypropyl) - N - (arylsulfonyl) - p-aminobenzoate compounds (XVIII),

and the N-(3-methoxy-2-hydroxypropyl) - N-(arylsulfonyl) - p - aminobenzoate compounds (XIX) are described and claimed in copending application Serial No. 41,884, filed July 31, 1948; the N-(3-acyloxy-2-ketopropyl) - N-(arylsulfonyl) - p-aminobenzoate compounds (XVII), the N-(3-halo-2-ketopropyl) - N-(arylsulfonyl) - p-aminobenzoate compounds (XIV), the N-(3-methoxy-2-ketopropyl) - N - (arylsulfonyl) - p-aminobenzoate compounds (VI) and the N-(3-hydroxy-2-ketopropyl) - N - (arylsulfonyl) -

p-aminobenzoate compounds (V) are described and claimed in copending application Serial No 41,889, filed July 31, 1948; and the N-(3,3-dialkoxy - 2 - hydroxypropyl) - N-(arylsulfonyl) - p-aminobenzoate compounds (I) and the N-(3,3-dialkoxy - 2 - ketopropyl) - N - (arylsulfonyl) - p-aminobenzoate compounds (IV) are described and claimed in a concurrently filed, copending application Serial No. 63,453.

The N-(2-formyl - 2 - hydroxyethyl) - N-(arylsulfonyl) - p-aminobenzoate compounds (II) and the N-(2-formyl-2-ketoethyl) - N-(arylsulfonyl) - p-aminobenzoate compounds (III) are new compounds first disclosed in the present application. They can be represented by the following generic formula (XXI)

XXI

wherein Y is from the group consisting of radicals having the formulae —CHOH— and —CO— and n and R' have the values previously given.

Esters which can be used as starting compounds in the process, with the production of the corresponding ester intermediates, include the methyl, ethyl, n-propyl, iso-propyl, butyl, amyl, hexyl, nonyl and other alkyl esters. As a matter of convenience, alkyl esters containing less than about 8 carbon atoms in the alkyl ester radicals are preferably used in the process, although insofar as is known any alkyl ester can be used.

Although starting compounds containing substantially any arylsulfonyl radical can be used in the process of the invention and in the preparation of the corresponding arylsulfonyl intermediates and final products, the preferred starting materials and intermediate products are those containing the p-toluenesulfonyl radical due to the ready availability of the p-toluenesulfonyl halides and to the generally crystalline nature of the p-toluenesulfonyl derivatives of compounds with which the present invention is concerned. Furthermore, it appears that the p-toluenesulfonyl radical can frequently be removed from the compounds involved herein, by splitting with hydrogen bromide as mentioned previously, somewhat more readily and with the formation of a smaller proportion of undesired by-products than is the case with some of the other arylsulfonyl radicals. The invention is, however, not limited to compounds containing the p-toluenesulfonyl radical and compounds containing other arylsulfonyl radicals, such as the o-toluenesulfonyl, naphthalenesulfonyl, methylnaphthalenesulfonyl radicals and others, can be used, if desired.

It should also be mentioned that compounds containing arylsulfonyl radicals having non-hydrocarbon substituents can be used in the process and the corresponding intermediate and final products prepared, provided only that the substituent is non-reactive under the reaction conditions. Such non-reactive substituents include chlorine, bromine, and the methoxy, phenoxy, nitro and similar radicals. It should be mentioned further that, although the present invention is concerned primarily with compounds wherein the sulfonyl derivative is an arylsulfonyl derivative, the process can also be carried out and the corresponding intermediate and final

products prepared using starting materials containing alkylsulfonyl, aralkylsulfonyl or cycloalkylsulfonyl radicals, such as the methanesulfonyl, ethanesulfonyl, cyclohexylsulfonyl, and phenylmethanesulfonyl radicals.

The conversion of an N-(3,3-dialkoxy-2-hydroxypropyl) - N-(arylsulfonyl) - p-aminobenzoate compound to an N-(2-formyl-2-hydroxyethyl) - N-(arylsulfonyl) - p-aminobenzoate compound is carried out conveniently according to the method of the present invention by treating the hydroxy acetal with an aqueous mineral acid, preferably at an elevated temperature. The process can, insofar as is known, be carried out using an N-(3,3-dialkoxy - 2 - hydroxypropyl) - N-(arylsulfonyl) - p-aminobenzoate compound containing any dialkyl acetal radical. From practical considerations, however, the preferred compounds are those wherein the alkyl radicals of the dialkyl acetal group each contains less than 8 carbon atoms. The reaction proceeds rapidly at or below the refluxing temperature of the mixture and is generally complete in from a few minutes to one hour or more. Satisfactory results have been obtained by heating the mixture for about fifteen minutes at about 60° C. Aqueous alcoholic mineral acid can also be used, if desired, and the reaction hastened by the greater solubility of the organic compound therein than in aqueous mineral acid. Following the heating, the water and excess acid, together with any alcohol present in the mixture, can be distilled in vacuo and a residue obtained consisting of the N-(2-formyl-2-hydroxyethyl) - N - (arylsulfonyl) - p-aminobenzoate compound in a form sufficiently pure for most uses. Such of these hydroxy aldehydes as are esters can be hydrolyzed to the corresponding acids by careful saponification and acidification.

The oxidation of an N-(2-formyl-2-hydroxyethyl) - N-(arylsulfonyl) - p-aminobenzoate compound to form an N-(2-formyl-2-ketoethyl) - N-(arylsulfonyl) - p-aminobenzoate compound can be carried out by heating the hydroxy aldehyde in an alcoholic or aqueous alcoholic medium with cupric acetate or chromic acetate. The oxidation is generally substantially complete in about one-half hour or less when the mixture is heated at from about 50° to about 80° C. In the case of oxidation using cupric acetate, a precipitate of copper oxide is formed and this can be removed readily by filtration. The alcohol or aqueous alcohol can then be distilled in vacuo and the N-(2-formyl-2-ketoethyl) - N-(arylsulfonyl) - p-aminobenzoate compound obtained as a residue which is generally in the form of a viscous, yellowish syrup.

When using chromic acetate as the oxidizing agent, the keto aldehyde can be recovered from the mixture by evaporating the solvent and washing the residue with water until the green color of chromium salts no longer persists in the washing. If desired, the residue can be dissolved in an organic solvent prior to the washing step to facilitate removal of the chromium salts. The N-(2-formyl-2-ketoethyl) - N - (arylsulfonyl) - p-aminobenzoate compounds which are esters can be hydrolyzed readily to the corresponding acids by careful saponification and acidification of the saponification mixture. The free acids can be recovered by substantially the same methods just described for the recovery of the esters.

Oxidation of an N-(3-hydroxy-2-ketopropyl) - N-(arylsulfonyl) - p-aminobenzoate compound to form an N-(2-formyl-2-ketoethyl) - N-(arylsul-

fonyl)-p-aminobenzoate compound is carried out in an alcoholic or aqueous alcoholic medium using cupric acetate or chromic acetate in a manner substantially the same as that described just previously for the oxidation of the hydroxy aldehyde compounds. The mixture is generally heated for from 5 to 30 minutes at from about 40° to about 80° C. and the keto aldehyde then recovered from the mixture as previously described.

Oxidation of an N-(3-methoxy-2-ketopropyl)-N-(arylsulfonyl)-p-aminobenzoate compound to form an N-(2-formyl-2-ketoethyl)-N-(arylsulfonyl)-p-aminobenzoate compound is carried out using chromic acetate in a manner entirely analogous to that described for the oxidation of the hydroxy aldehydes and the hydroxy ketones in the preceding paragraphs except that it is generally necessary to reflux the aqueous alcoholic reaction mixture for from one to several hours to insure substantial completion of the oxidation reaction. The keto aldehydes can be recovered from the reaction mixture using the methods previously described.

An N-(3,3-dialkoxy-2-ketopropyl)-N-(arylsulfonyl)-p-aminobenzoate compound can be hydrolyzed easily to an N-(2-formyl-2-ketoethyl)-N-(arylsulfonyl)-p-aminobenzoate compound by warming the keto acetal with aqueous or aqueous alcoholic mineral acid, preferably for from about 5 to about 30 minutes at from about 30° to about 80° C. The process can, insofar as is known, be carried out using an N-(3,3-dialkoxy-2-ketopropyl)-N-(arylsulfonyl)-p-aminobenzoate compound containing any dialkyl acetal radical. From practical considerations, however, the preferred compounds are those wherein the alkyl radicals of the dialkyl acetal group each contains less than 8 carbon atoms. The keto aldehyde can be recovered from the reaction mixture by evaporating the water and alcohol and washing the oily residue free of acid with water.

Reaction of an N-(2-formyl-2-ketoethyl)-N-(arylsulfonyl)-p-aminobenzoate compound with 2,4,5-triamino-6-hydroxypyrimidine to form an N-((2-amino-4-hydroxy-6-pteridyl)methyl)-N-(arylsulfonyl)-p-aminobenzoate compound can be carried out readily by mixing the substances, preferably together with anhydrous sodium acetate, in glacial acetic acid solution and allowing the mixture to stand for from one to several hours at room temperature. The 2,4,5-triamino-6-hydroxypyrimidine is generally used in the form of its dihydrochloride for greater ease in handling. The mixture is preferably stirred under an atmosphere of nitrogen or other inert gas. The reaction proceeds satisfactorily with the formation of the desired products in substantial yield. It should be mentioned that, although the preferred conditions have been given, the reaction can be carried out under conditions differing substantially from those recited.

Following the reaction in acetic acid, the product can be recovered by distilling the acetic acid in vacuo and washing the residue with water to remove traces of acetic acid and inorganic salts. The N-((2-amino-4-hydroxy-6-pteridyl)methyl)-N-(arylsulfonyl)-p-aminobenzoate compounds are thus obtained as highly colored residues which can, by the hydrolysis and cleavage procedure previously referred to, be converted into products containing a substantial proportion of a folic acid.

Among the N-(2-formyl-2-hydroxyethyl)-N-

(arylsulfonyl)-p-aminobenzoate compounds and N-(2-formyl-2-ketoethyl)-N-(arylsulfonyl)-p-aminobenzoate compounds which can be prepared by the method herein disclosed are included N-(2-formyl-2-hydroxyethyl)-N-(p-toluenesulfonyl)-p-aminobenzoic acid, ethyl N-(2-formyl-2-hydroxyethyl)-N-(p-toluenesulfonyl)-p-aminobenzoate, n-propyl N-(2-formyl-2-hydroxyethyl)-N-(alphanaphthylsulfonyl)-p-aminobenzoate, butyl N-(2-formyl-2-hydroxyethyl)-N-(p-chlorobenzenesulfonyl)-p-aminobenzoate, amyl N-(2-formyl-2-hydroxyethyl)-N-(benzenesulfonyl)-p-aminobenzoate, N-(2-formyl-2-hydroxyethyl)-N-(p-nitrobenzenesulfonyl)-p-aminobenzoic acid, N-(N-(2-formyl-2-hydroxyethyl)-N-(p-toluenesulfonyl)-p-aminobenzoyl)-glutamic acid, diethyl N-(N-(2-formyl-2-hydroxyethyl)-N-(o-toluenesulfonyl)-p-aminobenzoyl)-glutamate, di-n-butyl N-(N-(2-formyl-2-hydroxyethyl)-N-(p-chlorobenzenesulfonyl)-p-aminobenzoyl)-l-glutamate, N-(N-(2-formyl-2-hydroxyethyl)-N-(naphthalenesulfonyl)-p-aminobenzoyl)-glutamyl-glutamic acid, N-(N-(2-formyl-2-hydroxyethyl)-N-(p-nitrobenzenesulfonyl)-p-aminobenzoyl)-glutamyl-glutamic acid, N-(N-(2-formyl-2-hydroxyethyl)-N-(o-toluenesulfonyl)-p-aminobenzoyl)-glutamyl-glutamic acid, N-(N-(2-formyl-2-hydroxyethyl)-N-(alpha-naphthylsulfonyl)-p-aminobenzoate, butyl N-(2-formyl-2-ketoethyl)-N-(p-chlorobenzenesulfonyl)-p-aminobenzoate, amyl N-(2-formyl-2-ketoethyl)-N-(benzenesulfonyl)-p-aminobenzoate, N-(2-formyl-2-ketoethyl)-N-(p-nitrobenzenesulfonyl)-p-aminobenzoic acid, N-(N-(2-formyl-2-ketoethyl)-N-(p-toluenesulfonyl)-p-aminobenzoyl)-glutamic acid, diethyl N-(N-(2-formyl-2-ketoethyl)-N-(o-toluenesulfonyl)-p-aminobenzoyl)-glutamate, di-n-butyl N-(N-(2-formyl-2-ketoethyl)-N-(p-chlorobenzenesulfonyl)-p-aminobenzoyl)-l-glutamate, N-(N-(2-formyl-2-ketoethyl)-N-(naphthalenesulfonyl)-p-aminobenzoyl)-glutamyl-glutamic acid, and N-(N-(2-formyl-2-ketoethyl)-N-(p-nitrobenzenesulfonyl)-p-aminobenzoyl)-glutamyl-glutamyl-glutamic acid.

Certain advantages of the invention are apparent from the following examples which are given by way of illustration only and are not to be construed as limiting.

Example 1.—Ethyl N-(3,3-diethoxy-2-hydroxypropyl)-N-(p-toluenesulfonyl)-p-aminobenzoate

A mixture of one gram of the diethyl acetal of 2,3-oxidopropanal, 1.5 grams of ethyl N-(p-toluenesulfonyl)-p-aminobenzoate and two drops of pyridine was heated for twelve minutes at 130°-135° C. The clear melt which was formed was cooled and seeded with crystals of previously prepared ethyl N-(3,3-diethoxy-2-hydroxypropyl)-N-(p-toluenesulfonyl)-p-aminobenzoate. The partially crystalline mass was triturated with a mixture of six milliliters of petroleum naphtha and three milliliters of isopropanol and the mixture filtered. There was thus obtained 1.71 grams of ethyl N-(3,3-diethoxy-2-hydroxypropyl)-N-(p-toluenesulfonyl)-p-aminobenzoate melting at 89°-94° C. Repeated recrystallization of the product from isopropanol-petroleum naphtha raised the melting point to 91°-94° C. Hydrolysis of the ester with dilute alkali yields N-(3,3-di-

75

ethoxy - 2 - hydroxypropyl) - N - (p - toluenesulfonyl) - p - aminobenzoic acid.

Example 2.—Ethyl N-(3,3-diethoxy-2-ketopropyl)-N-(p-toluenesulfonyl)-p-aminobenzoate

Approximately 3.2 grams of ethyl N-(p-toluenesulfonyl)-p-aminobenzoate was reacted with the diethyl acetal of 2,3-oxidopropanal by the method described in Example 1. The crude reaction mixture prior to seeding was dissolved in 10 milliliters of glacial acetic acid and the solution mixed with a solution of one gram of chromic anhydride in 20 milliliters of glacial acetic acid. The mixture was allowed to stand at room temperature for about three hours and the acetic acid distilled in vacuo. The residue was triturated with ether and the mixture filtered. The ethereal filtrate was washed with water, dried and the ether volatilized. The residue consisted of ethyl N-(3,3-diethoxy-2-ketopropyl)-N-(p-toluenesulfonyl)-p-aminobenzoate in the form of an almost colorless oil.

N-(3,3-diethoxy-2-ketopropyl)-N-(p-toluenesulfonyl)-p-aminobenzoic acid is prepared by hydrolyzing its ethyl ester or by using N-(3,3-diethoxy-2-hydroxypropyl)-N-(p-toluenesulfonyl)-p-aminobenzoic acid instead of its ethyl ester in the procedure just described.

Example 3.—Ethyl N-(2-formyl-2-ketoethyl)-N-(p-toluenesulfonyl)-p-aminobenzoate

About 600 milligrams of ethyl N-(3,3-diethoxy-2-ketopropyl)-N-(p-toluenesulfonyl)-p-aminobenzoate is dissolved in about 6 milliliters of methanol and the mixture diluted with 2 milliliters of water containing 6 drops of concentrated aqueous hydrochloric acid. The solution is heated at about 60° C. for about 15 minutes and the methanol and water distilled in vacuo. There is thus obtained a residue containing ethyl N-(2-formyl-2-ketoethyl)-N-(p-toluenesulfonyl)-p-aminobenzoate.

N-(2-formyl-2-ketoethyl)-N-(p-toluenesulfonyl)-p-aminobenzoic acid is prepared by carefully hydrolyzing its ethyl ester with dilute alkali or by using N-(3,3-diethoxy-2-ketopropyl)-N-(p-toluenesulfonyl)-p-aminobenzoic acid instead of its ester in the above procedure.

Example 4.—Ethyl N-(2-formyl-2-hydroxyethyl)-N-(p-toluenesulfonyl)-p-aminobenzoate

Six hundred milligrams of ethyl N-(3,3-diethoxy-2-hydroxypropyl)-N-(p-toluenesulfonyl)-p-aminobenzoate was dissolved in 6 milliliters of methanol and diluted with 2 milliliters of water containing 6 drops of concentrated hydrochloric acid. The solution was heated at 60° C. for ten minutes and the methanol distilled in vacuo. The oily residue was dissolved in ether, washed free of acid with water, dried and the ether distilled in vacuo. There was thus obtained 600 milligrams of a light-colored oil containing a substantial proportion of ethyl N-(2-formyl-2-hydroxyethyl)-N-(p-toluenesulfonyl)-p-aminobenzoate.

N-(2-formyl-2-hydroxyethyl)-N-(p-toluenesulfonyl)-p-aminobenzoic acid is prepared by hydrolyzing its ethyl ester with dilute alkali or by using N-(3,3-diethoxy-2-hydroxypropyl)-N-(p-toluenesulfonyl)-p-aminobenzoic acid instead of its ester in the above procedure.

Example 5.—Ethyl N-(2-formyl-2-ketoethyl)-N-(p-toluenesulfonyl)-p-aminobenzoate

The oily product from Example 4 was dissolved in 20 milliliters of methanol and a solution of 300 milligrams of cupric acetate in 2 milliliters of water was added. The mixture was heated at about 60° C. for ten minutes. The copper oxide which precipitated was separated by filtering and the water and alcohol were distilled from the filtrate in vacuo. The residual oil, after drying in vacuo, weighed 600 milligrams and contained a substantial proportion of ethyl N-(2-formyl-2-ketoethyl)-N-(p-toluenesulfonyl)-p-aminobenzoate in the form of a viscous, yellow sirup.

N-(2-formyl-2-ketoethyl)-N-(p-toluenesulfonyl)-p-aminobenzoic acid is prepared in analogous manner using N-(2-formyl-2-hydroxyethyl)-N-(p-toluenesulfonyl)-p-aminobenzoic acid instead of its ester.

Example 6.—Ethyl N-(3-chloro-2-hydroxypropyl)-N-(p-toluenesulfonyl)-p-aminobenzoate

A mixture of five grams of ethyl N-(p-toluenesulfonyl)-p-aminobenzoate and 3.4 milliliters of epichlorohydrin was heated at 135° C. and two drops of pyridine added. A vigorous action ensued and after five minutes the mixture was cooled, dissolved in 50 milliliters of ethanol and treated three times with decolorizing carbon. The ethyl N-(3-chloro-2-hydroxypropyl)-N-(p-toluenesulfonyl)-p-aminobenzoate which remained upon volatilization of the ethanol and excess epichlorohydrin in vacuo was used in subsequent reactions without further purification.

Example 7.—Ethyl N-(3-chloro-2-ketopropyl)-N-(p-toluenesulfonyl)-p-aminobenzoate

The crude oily ethyl N-(3-chloro-2-hydroxypropyl)-N-(p-toluenesulfonyl)-p-aminobenzoate prepared from 30 grams of ethyl N-(p-toluenesulfonyl)-p-aminobenzoate and an excess of epichlorohydrin was dissolved in 150 milliliters of acetic acid and a mixture of 12 grams of sodium dichromate, 10 milliliters of sulfuric acid, 45 milliliters of water and 60 milliliters of acetic acid was added over a period of three hours while maintaining the mixture at 5° C. After stirring for an additional three hours, the oxidation mixture was diluted with water and extracted with ether. The ethereal extract was washed with sodium bicarbonate and the ether distilled. The residue of ethyl N-(3-chloro-2-ketopropyl)-N-(p-toluenesulfonyl)-p-aminobenzoate crystallized from dilute ethanol on prolonged standing. The crystallized product weighed 5.5 grams and after two crystallizations from dilute ethanol, melted at 106° to 113° C.

Example 8.—Ethyl N-(3-hydroxy-2-ketopropyl)-N-(p-toluenesulfonyl)-p-aminobenzoate

One gram of ethyl N-(3-chloro-2-ketopropyl)-N-(p-toluenesulfonyl)-p-aminobenzoate was dissolved in 20 milliliters of acetone and the solution diluted with 10 milliliters of water. One-half gram of barium carbonate was then added and the mixture stirred overnight at room temperature and then refluxed for two hours. The mixture was then filtered, partially concentrated, re-filtered and then concentrated. The thick liquid was dissolved in ether, washed with water and again concentrated to a viscous liquid. The ethyl N-(3-hydroxy-2-ketopropyl)-N-(p-toluenesul-

fonyl) -p-aminobenzoate thus obtained weighed 0.27 gram.

The ester can be hydrolyzed by careful saponification to form the free N-(3-hydroxy-2-ketopropyl) -N-(p-toluenesulfonyl) -p-aminobenzoic acid.

Example 9.—Ethyl N-(2-formyl-2-ketoethyl) -N-(p-toluenesulfonyl) -p-aminobenzoate

A mixture consisting of 770 milligrams of ethyl N-(3-hydroxy-2-ketopropyl) -N-(p-toluenesulfonyl) -p-aminobenzoate, 284 milligrams of cupric acetate, 20 milliliters of methanol and 2 milliliters of water was heated at about 60° C. for 10 minutes. The precipitated copper oxide was removed by filtration and the filtrate was distilled in vacuo to remove the methanol. The residue consisted of an aqueous and an oily layer. The oily layer was separated and dissolved in ethyl acetate and the copper salts washed from the solution with water. The ethyl acetate solution was then dried with sodium sulfate and the solvent removed by distillation in vacuo. There remained 600 milligrams of an oily residue containing a substantial proportion of ethyl N-(2-formyl-2-ketoethyl) -N-(p-toluenesulfonyl) -p-aminobenzoate.

Similar results are obtained using chromic acetate instead of cupric acetate.

N-(2-formyl-2-ketoethyl) -N-(p-toluenesulfonyl) -p-aminobenzoic acid is formed in similar manner using N-(3-hydroxy-2-ketopropyl) -N-(p-toluenesulfonyl) -p-aminobenzoic acid instead of its ethyl ester.

Example 10.—Ethyl N'-(2-amino-4-hydroxy-6-pteridyl)methyl -N-(p-toluenesulfonyl) -p-aminobenzoate

Six hundred milligrams of crude ethyl N-(2-formyl-2-ketoethyl) -N-(p-toluenesulfonyl) -p-aminobenzoate was dissolved in 15 milliliters of glacial acetic acid and the solution was added to a mixture of 150 milligrams of 2,4,5-triamino-6-hydroxypyrimidine dihydrochloride and 115 milligrams of anhydrous sodium acetate. The mixture was stirred for ninety minutes at room temperature under an atmosphere of nitrogen and the acetic acid was then removed from the mixture by distillation in vacuo. There was thus obtained a highly colored residue containing inorganic salts and ethyl N'-(2-amino-4-hydroxy-6-pteridyl)methyl -N-(p-toluenesulfonyl) -p-aminobenzoate.

In entirely analogous fashion 2,4,5-triamino-6-hydroxypyrimidine is reacted with N-(2-formyl-2-ketoethyl) -N-(p-toluenesulfonyl) -p-aminobenzoic acid to form N'-(2-amino-4-hydroxy-6-pteridyl)methyl -N-(p-toluenesulfonyl) -p-aminobenzoic acid.

Example 11.—Hydrolysis and cleavage of ethyl N'-(2-amino-4-hydroxy-6-pteridyl)methyl -N-(p-toluenesulfonyl) -p-aminobenzoate

The crude ethyl N'-(2-amino-4-hydroxy-6-pteridyl)methyl -N-(p-toluenesulfonyl) -p-aminobenzoate was dissolved in 3.5 milliliters of a 26 per cent by weight solution of hydrogen bromide in glacial acetic acid and 0.13 gram of phenol was added quickly. The mixture was stirred at room temperature for one hour and then poured into 30 milliliters of anhydrous ether. After mixing thoroughly and allowing to stand for a short time, the mixture of ether and suspended solid material was filtered and the residue washed twice with anhydrous ether and then dried in vacuo for several hours. The dry residue consisted of impure ethyl N'-(2-amino-4-hydroxy-6-

pteridyl)methyl -p-aminobenzoate. The product was hydrolyzed with dilute sodium hydroxide to convert the ester to the free acid. The product had an activity when bio-assayed with *Streptococcus fecalis* R. corresponding to a purity of 32 per cent of N'-(2-amino-4-hydroxy-6-pteridyl)methyl -p-aminobenzoic acid.

Example 12.—Diethyl N'-(N-(p-toluenesulfonyl) -p-aminobenzoyl) -l-glutamate

Thirty and nine-tenths grams of N-(p-toluenesulfonyl) -p-aminobenzoyl chloride and 23.9 grams of diethyl L(+)-glutamate hydrochloride were dissolved in 300 milliliters of ethylene dichloride and the solution cooled to between 0° and 10° C. The cold solution was stirred vigorously and 22.3 grams of triethylamine in 72 milliliters of ethylene dichloride was added slowly over a period of about 20 minutes. The temperature of the mixture was held between 10° and 20° C. during the addition of the triethylamine and the mixture then allowed to stand at room temperature for one hour. The mixture was then washed successively with water, dilute hydrochloric acid, saturated aqueous sodium bicarbonate and finally with water. The colorless solution thus obtained was dried with anhydrous sodium sulfate and naphtha was added until the solution became opalescent. The mixture was then cooled to cause crystallization and filtered. The crystals, after drying, consisted of 36 grams of diethyl N'-(N-(p-toluenesulfonyl) -p-aminobenzoyl) -l-glutamate melting at 124° to 126° C.

Example 13.—Diethyl N'-(N-(3,3-diethoxy-2-hydroxypropyl) -N-(p-toluenesulfonyl) -p-aminobenzoyl) -l-glutamate

One and six-tenths grams of the diethyl acetal of 2,3-oxidopropanal and five drops of pyridine were added to 4.77 grams of fused diethyl N'-(N-(p-toluenesulfonyl) -p-aminobenzoyl) -l-glutamate at 140° C. The mixture was stirred for about 30 minutes at 145° to 150° C. The highly colored mass consisted chiefly of diethyl N'-(N-(3,3-diethoxy-2-hydroxypropyl) -N-(p-toluenesulfonyl) -p-aminobenzoyl) -l-glutamate. It had an index of refraction without further purification of $N_D^{30} = 1.527$. N'-(N-(3,3-diethoxy-2-hydroxypropyl) -N-(p-toluenesulfonyl) -p-aminobenzoyl) -l-glutamic acid is formed by hydrolyzing the ester with dilute alkali.

Example 14.—Diethyl N'-(N-(3,3-diethoxy-2-ketopropyl) -N-(p-toluenesulfonyl) -p-aminobenzoyl) -l-glutamate

Five grams of diethyl N'-(N-(p-toluenesulfonyl) -p-aminobenzoyl) -l-glutamate and 1.9 grams of the diethyl acetal of 2,3-oxidopropanal were reacted substantially as by the method of Example 13. The crude diethyl N'-(N-(3,3-diethoxy-2-hydroxypropyl) -N-(p-toluenesulfonyl) -p-aminobenzoyl) -l-glutamate thus obtained was dissolved in 35 milliliters of glacial acetic acid and 1.7 grams of chromic anhydride was added to the solution. The mixture was stirred at room temperature for about two hours and then filtered. The filtrate was diluted with water and extracted with a mixture of benzene and ethyl acetate. The organic layer was separated, washed free of acid with water and dried over anhydrous sodium sulfate. The solvent was then distilled in vacuo and there was thus obtained 5.9 grams of diethyl N'-(N-(3,3-diethoxy-2-ketopropyl) -N-(p-toluenesulfonyl) -p-aminoben-

zoyl)-l-glutamate as a yellow sirup. Hydrolysis of the ester with dilute alcoholic sodium hydroxide forms N'-(N-(3,3-diethoxy-2-ketopropyl)-N-(p-toluenesulfonyl)-p-aminobenzoyl)-l-glutamic acid.

Example 15.—Diethyl N'-(N-(2-formyl-2-ketoethyl)-N-(p-toluenesulfonyl)-p-aminobenzoyl)-l-glutamate

A mixture consisting of 1.5 grams of diethyl N'-(N-(3,3-diethoxy-2-ketopropyl)-N-(p-toluenesulfonyl)-p-aminobenzoyl)-l-glutamate, 12 milliliters of methanol, 4 milliliters of water and 0.3 milliliter of concentrated aqueous hydrochloric acid was refluxed for about 20 minutes. The cooled solution was diluted with water, extracted with a mixture of benzene and ethyl acetate and the extract washed free of acid with water. The washed extract was dried with sodium sulfate and the ethyl acetate and benzene distilled in vacuo. The residue consisted of 1.1 gram of diethyl N'-(N-(2-formyl-2-ketoethyl)-N-(p-toluenesulfonyl)-p-aminobenzoyl)-l-glutamate in the form of a viscous mass.

N'-(N-(2-formyl-2-ketoethyl)-N-(p-toluenesulfonyl)-p-aminobenzoyl)-l-glutamic acid is prepared by careful hydrolysis of its diethyl ester with dilute alkali or by heating N'-(N-(3,3-diethoxy-2-ketopropyl)-N-(p-toluenesulfonyl)-p-aminobenzoyl)-l-glutamic acid with aqueous mineral acid as described above.

Example 16.—Diethyl N'-(N-(2-formyl-2-hydroxyethyl)-N-(p-toluenesulfonyl)-p-aminobenzoyl)-l-glutamate

The crude diethyl N'-(N-(3,3-diethoxy-2-hydroxypropyl)-N-(p-toluenesulfonyl)-p-aminobenzoyl)-l-glutamate obtained in Example 13 was dissolved in a mixture consisting of 25 milliliters of methanol, 10 milliliters of water and 1 milliliter of concentrated aqueous hydrochloric acid. The mixture was refluxed for 25 minutes and the methanol distilled in vacuo. The residue was dissolved in ethyl acetate and the solution washed with water and dried. Distillation of the ethyl acetate in vacuo gave 5.2 grams of a residue containing a substantial proportion of diethyl N'-(N-(2-formyl-2-hydroxyethyl)-N-(p-toluenesulfonyl)-p-aminobenzoyl)-l-glutamate in the form of a light-colored, viscous oil. The oil gave a yellow color with aqueous alkali and a positive test with Fehling's solution.

N'-(N-(2-formyl-2-hydroxyethyl)-N-(p-toluenesulfonyl)-p-aminobenzoyl)-l-glutamic acid is formed by careful saponification of its diethyl ester or by heating N'-(N-(3,3-diethoxy-2-hydroxypropyl)-N-(p-toluenesulfonyl)-p-aminobenzoyl)-l-glutamic acid with aqueous mineral acid as described above.

Example 17.—Diethyl N'-(N-(2-formyl-2-ketoethyl)-N-(p-toluenesulfonyl)-p-aminobenzoyl)-l-glutamate

Five grams of diethyl N'-(N-(2-formyl-2-hydroxyethyl)-N-(p-toluenesulfonyl)-p-aminobenzoyl)-l-glutamate was dissolved in 50 milliliters of methanol and the solution mixed with a solution of 1.8 grams of cupric acetate in a mixture of 50 milliliters of methanol and 10 milliliters of water. The mixture was heated at 60° C. for twelve minutes, the copper oxide was removed by filtering and the filtrate was distilled in vacuo to remove the methanol. The residue was dissolved in ethyl acetate and the solution was washed with water, dried and the ethyl acetate distilled in

vacuo. There was thus obtained 4.6 grams of a residue containing a substantial proportion of diethyl N'-(N-(2-formyl-2-ketoethyl)-N-(p-toluenesulfonyl)-p-aminobenzoyl)-l-glutamate in the form of a yellow sirup. The product gave a yellow color with aqueous alkali and a positive test with Fehling's solution. Similar results are obtained using chromic acetate instead of cupric acetate as the oxidizing agent.

N'-(N-(2-formyl-2-ketoethyl)-N-(p-toluenesulfonyl)-p-aminobenzoyl)-l-glutamic acid is formed by using N'-(N-(2-formyl-2-hydroxyethyl)-N-(p-toluenesulfonyl)-p-aminobenzoyl)-l-glutamic acid instead of its diethyl ester in the oxidation procedure described above.

Example 18.—2,3-epoxypropyl acetate (glycidol acetate)

A mixture of 98 grams of anhydrous potassium acetate, 10 grams of potassium carbonate and 250 milliliters of dry epichlorohydrin was refluxed for 25 hours. The mixture was cooled, filtered, and the filtrate fractionally distilled. A first fraction of unreacted epichlorohydrin was recovered and a fraction consisting of 73 grams of 2,3-epoxypropyl acetate boiling at 82° to 84° C. under a pressure of 40 millimeters was collected separately. The compound had an index of refraction $N_D^{20}=1.4201$.

Example 19.—Diethyl N'-(N-(3-acetoxy-2-hydroxypropyl)-N-(p-toluenesulfonyl)-p-aminobenzoyl)-l-glutamate

A mixture of 59.3 grams of diethyl N'-(N-(p-toluenesulfonyl)-p-aminobenzoyl)-l-glutamate and 12.7 grams of 2,3-epoxypropyl acetate was heated at 150° C. until a clear melt was formed. Five drops of pyridine were then added and the mixture heated at 145° to 150° C. for about one-half hour. The sirupy reaction mixture was then dissolved in 100 milliliters of benzene and the solution washed with water and dilute hydrochloric acid. The solution was dried and chromatographed on 1200 grams of alumina. The product was eluted with a solution of 5 per cent of ethanol in benzene. Evaporation of the alcohol and benzene gave a residue of 66 grams of diethyl N'-(N-(3-acetoxy-2-hydroxypropyl)-N-(p-toluenesulfonyl)-p-aminobenzoyl)-l-glutamate in the form of an oil having an index of refraction $N_D^{45}=1.5396$.

Example 20.—Diethyl N'-(N-(3-acetoxy-2-ketopropyl)-N-(p-toluenesulfonyl)-p-aminobenzoyl)-l-glutamate

A mixture was prepared consisting of 8.86 grams of diethyl N'-(N-(3-acetoxy-2-hydroxypropyl)-N-(p-toluenesulfonyl)-p-aminobenzoyl)-l-glutamate having an index of refraction $N_D^{45}=1.5396$, 50 milliliters of glacial acetic acid and 10 milliliters of propionic acid. The mixture was cooled to 0° C. and a solution of 1.65 grams of chromic anhydride in a mixture of 1.5 milliliters of water and 30 milliliters of glacial acetic acid was added slowly with stirring. The mixture was allowed to stand at about 5° C. for twelve hours and the solvent then distilled under reduced pressure. The residue was treated with a mixture of water and ether and the layers separated. The ether layer was washed twice with saturated sodium chloride solution then with saturated sodium bicarbonate solution and again with saturated sodium chloride solution. The washed ethereal solution was then dried with anhydrous magnesium sulfate and the ether distilled. There was thus obtained 6.1 grams of yellowish oily diethyl N'-(N-(3-acetoxy-

2 - ketopropyl) - N - (p - toluenesulfonyl) - p - amino-
benzoyl) - glutamate.

Example 21. — *Diethyl N' - (N - (3 - hydroxy - 2 - keto-
propyl) - N - (p - toluenesulfonyl) - p - amino-
benzoyl) - glutamate*

A mixture of 2.6 grams of diethyl N' - (N - (3 - acetoxy - 2 - ketopropyl) - N - (p - toluenesulfonyl) - p - aminobenzoyl - l - glutamate, 0.1 gram of p - toluenesulfonic acid and 40 milliliters of absolute ethanol was refluxed for three hours and then distilled slowly until 25 milliliters of distillate had been collected. An additional 40 milliliters of absolute ethanol was added and the mixture again refluxed for 2.25 hours. The mixture was then concentrated in vacuo and the sirupy residue taken up in ether and washed successively with 3 portions of water and one portion of saturated sodium chloride solution. The ethereal solution was then dried over anhydrous magnesium sulfate and the ether evaporated in vacuo. There was thus obtained 2 grams of viscous diethyl N' - (N - (3 - hydroxy - 2 - ketopropyl) - N - (p - toluenesulfonyl) - p - aminobenzoyl) - l - glutamate having a specific rotation at 25° C. in absolute ethanol of -18°. The product can be purified and obtained in solid form using Girard's reagent "F." Careful hydrolysis of the ester with dilute alkali gives N' - (N - (3 - hydroxy - 2 - ketopropyl) - N - (p - toluenesulfonyl) - p - aminobenzoyl) - glutamic acid.

Example 22. — *Diethyl N' - (N - (2 - formyl - 2 - keto-
ethyl) - N - (p - toluenesulfonyl) - p - aminoben-
zoyl) - l - glutamate*

A solution of 300 milligrams of solid diethyl N' - (N - (3 - hydroxy - 2 - ketopropyl) - N - (p - toluenesulfonyl) - p - aminobenzoyl) - l - glutamate in 30 milliliters of absolute ethanol containing a catalytic amount of p - toluenesulfonic acid and sufficient chromic acetate to give the solution a permanent green color was refluxed for 3 hours. The solution was then distilled in vacuo to remove most of the ethanol and the organic portion of the residue was dissolved in ethyl acetate. The ethyl acetate solution was washed with water and dried and the ethyl acetate distilled in vacuo. There was thus obtained 290 milligrams of oily residue containing a substantial proportion of diethyl N' - (N - (2 - formyl - 2 - ketoethyl) - N - (p - toluenesulfonyl) - p - aminobenzoyl) - l - glutamate. Similar results were obtained using crude, oily diethyl N' - (N - (3 - hydroxy - 2 - ketopropyl) - N - (p - toluenesulfonyl) - p - aminobenzoyl) - l - glutamate which had not been purified using Girard's reagent.

N' - (N - (2 - formyl - 2 - ketoethyl) - N - (p - toluenesulfonyl) - p - aminobenzoyl) - l - glutamic acid is formed by oxidation of N' - (N - (3 - hydroxy - 2 - ketopropyl) - N - (p - toluenesulfonyl) - p - aminobenzoyl) - l - glutamic acid with chromic acetate by the procedure just given.

Example 23. — *Diethyl N' - (N - (2 - formyl - 2 - keto-
ethyl) - N - (p - toluenesulfonyl) - p - aminoben-
zoyl) - l - glutamate*

A solution of 350 milligrams of solid diethyl N' - (N - (3 - hydroxy - 2 - ketopropyl) - N - (p - toluenesulfonyl) - p - aminobenzoyl - l - glutamate and 142 milligrams of cupric acetate in a mixture of 20 milliliters of methanol and 2 milliliters of water was heated at 60° C. for 10 minutes. The solution was filtered to remove precipitated copper oxide and then distilled in vacuo to remove methanol. The residue was dissolved in ethyl acetate and the solution was washed well with

water, dried with sodium sulfate and distilled in vacuo to remove the ethyl acetate. There was thus obtained 330 milligrams of an oily residue containing a substantial proportion of diethyl N' - (N - (2 - formyl - 2 - ketoethyl) - N - (p - toluenesulfonyl) - p - aminobenzoyl) - l - glutamate. Similar results were obtained using crude, oily diethyl N' - (N - (3 - hydroxy - 2 - ketopropyl) - N - (p - toluenesulfonyl) - p - aminobenzoyl) - l - glutamate which had not been purified using Girard's reagent.

N' - (N - (3 - hydroxy - 2 - ketopropyl) - N - (p - toluenesulfonyl) - p - aminobenzoyl) - l - glutamic acid is oxidized with cupric acetate in similar manner to form N' - (N - (2 - formyl - 2 - ketoethyl) - N - (p - toluenesulfonyl) - p - aminobenzoyl) - l - glutamic acid.

Example 24. — *Diethyl N' - (N - (3 - methoxy - 2 -
hydroxypropyl) - N - (p - toluenesulfonyl) - p -
aminobenzoyl) - l - glutamate*

A mixture of 7.2 grams of diethyl N' - (N - (p - toluenesulfonyl) - p - aminobenzoyl) - l - glutamate and 1.45 grams of 1,2-epoxy-2-methoxypropane was heated in an oil bath at 145° C. until melted and five drops of pyridine then added. The mixture was stirred at 145° to 150° C. for thirty minutes and then dissolved in 50 milliliters of benzene. The benzene solution was washed three times with 20 milliliter portions of dilute sulfuric acid and then with water until the washings were neutral. The benzene solution was then dried with anhydrous sodium sulfate, treated twice with 0.5 gram portions of decolorizing charcoal and filtered. The benzene was then evaporated from the filtrate under reduced pressure and there were thus obtained 8.0 grams of diethyl N' - (N - (3 - methoxy - 2 - hydroxypropyl) - N - (p - toluenesulfonyl) - p - aminobenzoyl) - l - glutamate as an almost colorless, somewhat viscous liquid having an index of refraction $N_D^{20} = 1.538$.

In similar fashion ethyl N - (p - toluenesulfonyl) - p - aminobenzoate is reacted with 1,2-epoxy-3-methoxypropane to form ethyl N - (3 - methoxy - 2 - hydroxypropyl) - N - (p - toluenesulfonyl) - p - aminobenzoate.

Example 25. — *Diethyl N' - (N - (3 - methoxy - 2 - keto-
propyl) - N - (p - toluenesulfonyl) - p - aminoben-
zoyl) - l - glutamate*

A solution of 0.536 gram of chromic oxide in about 5 milliliters of water was added slowly at 20° C. and with stirring to a solution of 2 grams of diethyl N' - (N - (3 - methoxy - 2 - hydroxypropyl) - N - (p - toluenesulfonyl) - p - aminobenzoyl) - l - glutamate in 19 milliliters of glacial acetic acid. The mixture was allowed to stand for three and one-half hours and was then poured into water and extracted with benzene. The benzene layer was washed thoroughly with water and the benzene vaporized in vacuo. There was thus obtained a residue consisting of 1.3 grams of diethyl N' - (N - (3 - methoxy - 2 - ketopropyl) - N - (p - toluenesulfonyl) - p - aminobenzoyl) - l - glutamate having an index of refraction $N_D^{26} = 1.5440$ and melting at 82° to 84° C.

In a similar manner ethyl N - (3 - methoxy - 2 - hydroxypropyl) - N - (p - toluenesulfonyl) - p - aminobenzoate is oxidized with chromic oxide to form ethyl N - (3 - methoxy - 2 - ketopropyl) - N - (p - toluenesulfonyl) - p - aminobenzoate. N - (3 - methoxy - 2 - ketopropyl) - N - (p - toluenesulfonyl) - p - aminobenzoic acid and N' - (N - (3 - methoxy - 2 - ketopropyl) - N - (p - toluenesulfonyl) - p - amino-

benzoyl)-l-glutamic acids are formed by careful saponification of their respective ethyl esters.

Example 26. — Diethyl N'-(N-(2-formyl-2-ketoethyl)-N-(p-toluenesulfonyl)-p-aminobenzoyl)-l-glutamate

A solution of 300 milligrams of crystalline diethyl N'-(N-(3-methoxy-2-ketopropyl)-N-(p-toluenesulfonyl)-p-aminobenzoyl)-l-glutamate and 25 milliliters of absolute ethanol containing a catalytic amount of p-toluenesulfonic acid and sufficient chromic acetate to give the solution a permanent green color was refluxed for 3 hours. The solution was then evaporated to remove ethanol and the residue extracted with ethyl acetate. The extract was washed with water, dried and the ethyl acetate evaporated in vacuo. There remained a residue of 310 milligrams containing a substantial proportion of diethyl N'-(N-(2-formyl-2-ketoethyl)-N-(p-toluenesulfonyl)-p-aminobenzoyl)-l-glutamate which was used in a subsequent experiment without further purification.

In a similar manner, ethyl N-(3-methoxy-2-ketopropyl)-N-(p-toluenesulfonyl)-p-aminobenzoate is oxidized by chromic acetate with the formation of ethyl N-(2-formyl-2-ketoethyl)-N-(p-toluenesulfonyl)-p-aminobenzoate.

N-(2-formyl-2-ketoethyl)-N-(p-toluenesulfonyl)-p-aminobenzoic acid and N'-(N-(2-formyl-2-ketoethyl)-N-(p-toluenesulfonyl)-p-aminobenzoyl)-l-glutamic acid are formed by careful saponification of their ethyl esters or by oxidizing N-(3-methoxy-2-ketopropyl)-N-(p-toluenesulfonyl)-p-aminobenzoic acid or N'-(N-(3-methoxy-2-ketopropyl)-N-(p-toluenesulfonyl)-p-aminobenzoyl)-l-glutamic acid, respectively, with chromic acetate according to the method just described.

Example 27. — Diethyl N'-(N-((2-amino-4-hydroxy-6-pteridyl)methyl)-N-(p-toluenesulfonyl)-p-aminobenzoyl)-l-glutamate

Three hundred thirty milligrams of crude diethyl N'-(N-(2-formyl-2-ketoethyl)-N-(p-toluenesulfonyl)-p-aminobenzoyl)-l-glutamate was dissolved in 11 milliliters of glacial acetate acid and the solution mixed with 107 milligrams of 2,4,5-triamino-6-hydroxypyrimidine dihydrochloride and 82 milligrams of sodium acetate. The mixture was stirred at room temperature under an atmosphere of nitrogen for about ninety minutes and then concentrated in vacuo to remove most of the acetic acid. Washing of the residue with water gave a product consisting principally of diethyl N'-(N-((2-amino-4-hydroxy-6-pteridyl)methyl)-N-(p-toluenesulfonyl)-p-aminobenzoyl)-l-glutamate.

2,4,5-triamino-6-hydroxypyrimidine is reacted with N'-(N-(2-formyl-2-ketoethyl)-N-(p-toluenesulfonyl)-p-aminobenzoyl)-l-glutamic acid in a manner similar to that just described to form N'-(N-((2-amino-4-hydroxy-6-pteridyl)methyl)-N-(p-toluenesulfonyl)-p-aminobenzoyl)-l-glutamic acid.

Example 28. — Hydrolysis and cleavage of diethyl N'-(N-((2-amino-4-hydroxy-6-pteridyl)methyl)-N-(p-toluenesulfonyl)-p-aminobenzoyl)-l-glutamate

The crude reaction product containing diethyl N'-(N-((2-amino-4-hydroxy-6-pteridyl)methyl)-N-(p-toluenesulfonyl)-p-aminobenzoyl)-l-glutamate obtained in Example 27 was mixed with 130 milligrams of phenol and 2.5

milliliters of a 26 per cent solution of hydrogen bromide in glacial acetic acid. The mixture was stirred for ninety minutes at room temperature and then diluted with anhydrous ether. Ethyl pteroyl glutamate hydrobromide separated from the mixture as a brown, hygroscopic solid which was recovered by filtration. The brown solid was dissolved in about two milliliters of methanol and ten per cent aqueous sodium hydroxide was added to give a strongly alkaline solution. The alkaline mixture was allowed to stand for ninety minutes at 40° C. and then acidified with mineral acid to pH 3.0. The solution was then diluted with five milliliters of water, cooled in an ice bath for one hour and then centrifuged. The solid residue was washed with three milliliters of water and three times with three milliliters of acetone and dried in vacuo over sulfuric acid. There was thus obtained 89 milligrams of pteroyl glutamic acid which, upon microbiological assay with *Lactobacillus casei* had an activity of 48.8 per cent of that of the pure natural acid.

We claim:

1. A compound having the formula

wherein R' is from the group consisting of hydrogen and the alkyl radicals, n is from the group consisting of zero and the positive integers 1 to 7, inclusive, and Y is from the group consisting of radicals having the formulae —CHOH— and —CO—.

35 2. A compound as claimed in claim 1 wherein R' is hydrogen.

3. A compound as claimed in claim 1 wherein R' is an alkyl radical.

40 4. A compound as claimed in claim 1 wherein n is zero.

5. A compound as claimed in claim 1 wherein n is the positive integer 1.

6. A compound as claimed in claim 1 wherein the arylsulfonyl radical is the p-toluenesulfonyl radical.

45 7. A compound having the formula

wherein R' is from the group consisting of hydrogen and the alkyl radicals and n is from the group consisting of zero and the positive integers 1 to 7, inclusive.

55 8. Ethyl N-(2-formyl-2-hydroxyethyl)-N-(p-toluenesulfonyl)-p-aminobenzoate.

9. Diethyl N'-(N-(2-formyl-2-hydroxyethyl)-N-(p-toluenesulfonyl)-p-aminobenzoyl)-glutamate.

60 10. A compound having the formula

wherein R' is from the group consisting of hydrogen and the alkyl radicals and n is from the group consisting of zero and the positive integers 1 to 7, inclusive.

70 11. Ethyl N-(2-formyl-2-ketoethyl)-N-(p-toluenesulfonyl)-p-aminobenzoate.

12. Diethyl N'-(N-(2-formyl-2-ketoethyl)-N-(p-toluenesulfonyl)-p-aminobenzoyl)-glutamate.

21

13. The method which includes: reacting a keto-aldehyde having the formula

wherein R' is from the group consisting of hydrogen and the alkyl radicals and n is from the group consisting of zero and the positive integer 1, with 2,4,5-triamino-6-hydroxypyrimidine to form a compound having the formula

wherein R' and n have the values given.

14. The method of claim 13 wherein n is zero.

15. The method of claim 13 wherein n is the positive integer 1.

16. The method of claim 13 wherein R' is hydrogen.

17. The method of claim 13 wherein R' is an alkyl radical.

18. The method of claim 13 wherein the arylsulfonyl radical is the p-toluenesulfonyl radical.

19. The method of claim 13 wherein the keto-aldehyde is ethyl N-(2-formyl-2-ketoethyl)-N-(p-toluenesulfonyl)-p-aminobenzoate.

20. The method of claim 13 wherein the keto-aldehyde is diethyl N'-(N-(2-formyl-2-keto-

ethyl)-N-(p-toluenesulfonyl)-p-aminobenzoyl)-glutamate.

21. The method which includes: hydrolyzing a keto acetal having the formula

wherein R' is from the group consisting of hydrogen and the alkyl radicals and n is from the group consisting of zero and the positive integer 1, to form a keto aldehyde having the formula

and, subsequently, reacting the latter compound with 2,4,5-triamino-6-hydroxypyrimidine to form a compound having a formula

R' and n having the values given.

22. The method of claim 21 wherein the acetal is ethyl N-(3,3-diethoxy-2-ketopropyl)-N-(p-toluenesulfonyl)-p-aminobenzoate.

23. The method of claim 21 wherein the acetal is diethyl N'-(3,3-diethoxy-2-ketopropyl)-N-(p-toluenesulfonyl)-p-aminobenzoyl-glutamate.

24. The method which includes: oxidizing a hydroxy aldehyde having the formula

22

wherein R' is from the group consisting of hydrogen and the alkyl radicals and n is from the group consisting of zero and the positive integer 1, to form a keto aldehyde having the formula

and, subsequently, reacting the latter compound with 2,4,5-triamino-6-hydroxypyrimidine to form a compound having the formula

R' and n having the values given.

25. The method of claim 24 wherein the hydroxy aldehyde is ethyl N-(2-formyl-2-hydroxyethyl)-N-(p-toluenesulfonyl)-p-aminobenzoate.

26. The method of claim 24 wherein the hydroxy aldehyde is diethyl N'-(N-(2-formyl-2-hydroxyethyl)-N-(p-toluenesulfonyl)-p-aminobenzoyl)-glutamate.

27. The method of claim 24 wherein the hydroxy aldehyde is oxidized with cupric acetate.

28. The method of claim 24 wherein the hydroxy aldehyde is oxidized with chromic acetate.

29. The method which includes: hydrolyzing a hydroxy acetal having the formula

wherein R' is from the group consisting of hydrogen and the alkyl radicals and n is from the group consisting of zero and the positive integer 1, to form a hydroxy aldehyde having the formula

oxidizing the hydroxy aldehyde to form a keto aldehyde having the formula

and, subsequently, reacting the latter compound with 2,4,5-triamino-6-hydroxypyrimidine to form a compound having the formula

R' and n having the values given.

30. The method of claim 29 wherein the hydroxy acetal is ethyl N-(3,3-diethoxy-2-hydroxypropyl)-N-(p-toluenesulfonyl)-p-aminobenzoate.

31. The method of claim 29 wherein the hydroxy acetal is diethyl N'-(N-(3,3-diethoxy-2-hydroxypropyl)-N-(p-toluenesulfonyl)-p-aminobenzoyl)-glutamate.

23

32. The method which includes: oxidizing a keto alcohol having the formula

wherein R' is from the group consisting of hydrogen and the alkyl radicals and n is from the group consisting of zero and the positive integer 1, to form a keto aldehyde having the formula

and, subsequently, reacting the latter compound with 2,4,5 - triamino - 6 - hydroxypyrimidine to form a compound having the formula

R' and n having the values given.

33. The method of claim 32 wherein the keto alcohol is oxidized with cupric acetate.

34. The method of claim 32 wherein the keto alcohol is oxidized with chromic acetate.

35. The method of claim 32 wherein the keto alcohol is ethyl N - (3 - hydroxy - 2 - ketopropyl) - N - (p - toluenesulfonyl) - p - aminobenzoate.

36. The method of claim 32 wherein the keto alcohol is diethyl N' - (N - (3 - hydroxy - 2 - ketopropyl) - N - (p - toluenesulfonyl) - p - aminobenzoyl) -glutamate.

37. The method which includes: oxidizing a methoxy ketone having the formula

wherein R' is from the group consisting of hydrogen and the alkyl radicals and n is from the

24

group consisting of zero and the positive integer 1, to form a keto aldehyde having the formula

and, subsequently, reacting the latter with 2,4,5 - triamino - 6 - hydroxypyrimidine to form a compound having the formula

R' and n having the values given.

38. The method of claim 37 wherein the methoxy ketone is ethyl N - (3 - methoxy - 2 - ketopropyl) - N - (p - toluenesulfonyl) - p - aminobenzoate.

39. The method of claim 37 wherein the methoxy ketone is diethyl N' - (N - (3 - methoxy - 2 - ketopropyl) - N - (p - toluenesulfonyl) - p - aminobenzoyl) -glutamate.

40. The method of claim 37 wherein the methoxy ketone is oxidized with chromic acetate.
